AUTOMATIC FOLDING TABLE

Charles Forsberg, St. Louis, Mo.

Application December 5, 1938, Serial No. 243,967

2 Claims. (Cl. 311—2)

This invention relates to a combined automatic folding table and lamp with self-adjusting leg, and pertains more particularly to that class of tables used for ornamentation and for card playing purposes and having swingable leaves.

Another object is to provide a table having a fixed center piece with circumferentially disposed swingable leaves or table top sections.

A further object is to provide a table having downwardly swingable leaves which are operable by a centrally disposed post having parts cooperable with the leaves.

A still further object is to provide a table with downwardly swingable leaves and foldable corner sections operably connected to the leaves.

Another still further object is to provide a foldable table with a cooperable lamp post to be used in folding or unfolding the table.

Still another object is to provide a supporting leg for a table or the like with improved adjusting means.

Other objects and advantages will appear as this description progresses and by reference to the drawings, in which:

Figure 1 is a side elevation of this improved table.

Figure 2 is a side elevation of the table having its leaves in downwardly swung positions.

Figure 3 is a horizontal sectional view taken approximately on the line 3—3 of Fig. 1.

Figure 4 is an enlarged inverted horizontal sectional view of a portion of the table top taken approximately on the line 4—4 of Fig. 1.

Figure 5 is an enlarged horizontal fragmentary sectional view taken approximately on the line 5—5 of Fig. 2.

Figure 6 is an enlarged vertical fragmentary sectional view taken approximately on the line 6—6 of Fig. 3.

Figure 7 is an enlarged horizontal fragmentary sectional view taken approximately on the line 7—7 of Fig. 1.

Figure 8 is an enlarged vertical fragmentary sectional view taken approximately on the line 8—8 of Fig. 7.

Figure 9 is an enlarged vertical fragmentary sectional view similar to Fig. 8.

Figure 10 is an enlarged vertical fragmentary sectional view taken approximately on the line 10—10 of Fig. 2.

Figure 11 is an enlarged vertical fragmentary sectional view taken approximately on the line 11—11 of Fig. 10.

Referring by numerals to the accompanying drawings, 12 designates a center piece which is

fixed at 13 to an under-engaged frame 14, said frame being secured at 15 to the upper end of a tubular standard 16 having extending curved supporting legs 17 at its lower end.

5 The frame 14 at each corner is provided with a pair of ears 18, one of the ears of each pair of ears forming end support for respective pintles 19, each of which is borne by the inner end of a respective table leaf 20.

10 As shown more clearly in Figs. 3 and 4, each pintle 19 is disposed parallel to a respective side edge 21 of the center piece 12 and each table leaf 20 on its side edge is provided with a hinge part 22 for cooperation with a respective hinge part 23 of respective table top sections 24, the hinge parts 22 and 23 being cooperably secured by respective pintles 25, and interposed between respective pairs of table top sections 24 and hinged thereto, as shown at 26, is a respective top section 27.

15 Secured to the under-side of each section 27 is a member 28 which is of a length to under-lap portions of adjacent sections 24, and depended from each member 28 is a bracket 29 having end disposed ears 30 supporting a pin 31, and engaged on the ends of each pin is the yoke end 32 of respective operating rods 33, the depending ends of each rod being pivotally secured at 34 to respective ears 35 of a cross-head 36.

20 Slidably mounted in the standard 16 is a post 37 which extends upwardly through a bushing 38 in the center piece 12, the upper extending end of the post supporting a lamp 39, and the lower extending end of the post being slidably secured in the cross-head 36 by a transversely disposed pin 40 which is borne by the cross-head and engaged in opposing longitudinal slots 41 which are formed in the post 37.

25 The cross-head 36 is cylindrical and is adapted to have a sliding fit within the standard 16 and supported thereby are the ears 35, each extending through a respective vertical slot 41a formed in the standard 16. The upper end 42 of the cross-head 36 is tapered, and formed in the wall of the cross-head beneath the tapered end 42 is a pair of diametrically disposed apertures 43, and for cooperation therewith are respective spring actuated plungers 44 which are supported in respective brackets 45 secured to the standard 16, each plunger 44 also being engaged in respective apertures formed in the standard 16 (Figs. 7, 8 and 9).

30 The lower extending end of the post 37 which is disposed within the cross-head 36, is provided with a beveled portion 45 which is adapted to engage the tapered end of respective plungers

44, said beveled portion 45 however, being normally held in abutment with the shoulder 46 of the cross-head by the coil spring 47, which is disposed inside of the support 37 in abutment at one end with a ring washer 48 and in abutment at its opposite end with the seat 49 which rests on the cross-head pin 40.

The electrical current supply to the bulbs of the lamp 39 may be provided by entraining the electrical extension cord 50 into the bottom of the standard 16 and through the post 37, in the manner as shown in Figs. 8 and 9.

When the table leaves 20 and connecting top sections 24 and 27 are upwardly unfolded, they will be disposed in a horizontal plane, as shown in Fig. 1, where the top surfaces thereof will approximately parallel the center piece 12. When it is desired to downwardly fold the table leaves and their connecting table top sections to the approximate positions shown in Fig. 2, the post 37 is grasped adjacent the lamp 39 and a downward pressure is applied thereto, thereby moving the beveled portion 45 at the lower end of the post 37 away from the shoulder 46 of the cross-head 36 against the pressure of the spring 47, the downward movement given to the post 37 engaging the beveled portion 45 against the tapered ends of the plungers 44, thereby forcing the plungers outward to the approximate positions shown in Fig. 9, and simultaneous therewith, the cross-head pin 40 will be engaged by the upper ends of the slots 41 of the post 37 and the cross-head 36 will be moved downward in the standard 16, and the ears 35 thereof to which the operating rods 33 are connected will likewise be moved downwardly, the downward pulling force thus created on the rods 33 effecting the interposed table top sections 27 and causing them to transfer a pulling strain on respective table top sections 24 and the respective leaves 20, whereby the leaves 20 will be swung downwardly on their respective pintles 19 as respective sections 27 assume folding positions with respective sidewise disposed sections 24, in the manner as shown in Fig. 2 and as detailed in Fig. 5.

When the table is folded, as shown in Fig. 2, it can be conveniently moved or carried by grasping the post 37 beneath the lamp without any unfolding action being effected by the post on the sections 24 and 27 as the lifting strain imparted from the post to the rods 33 will be such as to tend to swing the sections 27 further inward. However, to unfold the folded parts of the table top, when lifting effort is applied to the post 37, the manipulator should engage and outwardly swing one of the sections 27 to an approximate vertical position so that the lifting movement on the post 37 when transferred to the rods 30 will cause the upper ends of the rods to outwardly swing as the cross-head 36 is elevated by the post by the upper edge of the beveled portion 45 of the post abutting the shoulder 46 of the cross-head, the upper tapered end 42 of the cross-head forcing back the plungers 44, and when the cross-head has been drawn by the post 37 to its maximum height, the plunger apertures 43 thereof will be engaged by respective plungers 44 for holding the cross-head in its elevated position, as well as the table top sections 20, 24 and 27.

It is to be noted that each member 28 which under-engages respective sections 24 when the table sections are disposed in a horizontal plane, 75

will serve as a reinforcement to maintain said sections in the same plane.

A covering 51 of the approximate combined area of the horizontal surfaces of the leaves 20 and sections 24 and 27 is mounted over said parts, the covering however, being secured by adhesive material to the surfaces of the leaves 20 but not to the surfaces of the sections 24 and 27, for the reason that it is necessary that the covering material of the diagonal corners of the table top be free of the respective folding sections 24 and 27, in order to eliminate binding or drawing of the covering material at these folding sections during folding operation. To eliminate the binding of the covering at the diagonal corners of the table top during folding of respective sections 24 and 27, the covering at the diagonal corners is secured at 52 to the outer end of a flap 53 which is secured at its opposite end at 54 to a respective top section 24, as shown in Figs. 3 and 5. The flaps 53 by reason of being secured to respective sections 27, will hold the diagonal corners of the covering inward during the folding operation and at the same time will omit binding or pulling strains on the covering at the diagonal corners, and when the respective sections 24 and 27 are unfolded to horizontal positions the flaps 53 will assume straightened-out underlying positions.

With the arrangement of the post 37 extending above the table top, a holding tray or shelf can be supported from the post above the table top, if desired.

In Fig. 10, one of the supporting legs 17 is provided with adjusting means for the foot 55 thereof so that said foot may be moved in adjustment in the event there is unevenness of floor engagement of the table legs. In this connection, the foot 55 forms part of a lever 56 which is intermediately pivoted at 57 to one of the legs 17, said lever being connected at its extending end to a coil spring 58 which is secured at 59 to the said leg 17, and connected at 60 to the lever 56 is a pin 61 having its depending end slidably mounted in an opening 62 of a rockable cross bar 63 which is pivotally supported at 64 in the side members 65, and fixed to said cross bar and extending upwardly therefrom is a lever 66 which is connected at 67 to a pull rod 68 which is slideable intermediate its length in a cross bar 69, and mounted on the pull rod 68 between the cross bar 69 and the pivotal connection 67 is a coil spring 74. The cross bar 69 is supported between the side members 65, and secured at 70 to the other end of the pull rod 68 is a lever 71 which is intermediately pivoted at 72 to the leg 17 which is oppositely disposed from the other leg to which the lever 56 is pivotally secured. The lever 71 is provided with a foot engaging portion 73 which extends through an opening in the leg 17 to which said lever is pivotally secured.

For leveling the leg 17 or rather the feet thereof, for floor engagement, the foot portion 73 of the lever 71 is engaged and pressed downwardly thereby exerting a pull on the rod 68 and compressing the coil spring 74 thereon and at the same time the cross bar 63 is rocked by pulling exertion on the lever 66 which extends upwardly from said cross bar.

When the cross bar 63 is rocked, binding effect of diagonally disposed edges of the opening 62 of the cross bar will be released from the pin 61, and in the event that the foot 55 is elevated from the floor the spring 58 will become active on the lever 56 to swing said lever and force the foot 55

against the floor. When the operator releases pressure from the foot portion 73 of the lever 71, the spring 74 on the pull rod 68 will become effective thereon to actuate the lever 66 to rock the cross bar 63 and the opening 62 thereof into binding engagement on the pin 61 for holding the foot 55 in its lowered position against the floor.

In the event the foot 55 is bearing against the floor in a manner to prevent a pair of oppositely disposed legs from floor engagement, when the cross bar 63 is rocked by foot pressure on the lever 71 the pin 61 will be released in the cross bar so that the pin can move downward therein to permit the foot 55 to be moved upwardly to a position wherein leveling of the pair of legs which were heretofore above the floor, is permitted. Obviously, release of the foot lever 71 will permit the cross bar 63 to be rocked into locking engagement with the pin 61 by action of the spring 74 on the lever 66 of the cross bar 63, thereby preventing displacement of the foot 55 from its floor leveling position.

From the foregoing, it is obvious that a unique table having foldable top sections is provided with improved means for folding the sections, and while a preferred embodiment of the invention is shown, it is to be understood that various changes, size, shape and arrangements of parts, may be resorted to without departing from the spirit and scope of the invention of the claims hereto.

What I claim is:

1. A table having downwardly swingable table top sections, a tubular support for the table, and means slidable in said support and having engaging cooperation with certain of said sections for elevating and lowering said sections, said means comprising a post slidably mounted in said support and tapered on its inner end and having its outer end extending above the table top, a spring actuated slidable element mounted on the inner end of said post and tapered on one end, rods connected at one end to certain of said sections and at their other ends to said element, and locking plungers for said element adapted to be released by the tapered ends of said post and said element respectively.
- 10 2. A table having a center piece, a series of downwardly swingable sections hinged to one another and surrounding said center piece and hinged thereto, a standard supporting said center piece, means cooperable with said sections for elevating them to horizontal positions, said means comprising an element slidable in said standard and having tapered ends, rods connecting said element and certain of said sections, and spring actuated plungers cooperable with the tapered ends of said element to lock the element in either an elevated or lowered position in said standard.
